UNITED STATES PATENT OFFICE.

CARL I. OSTERBERG, OF CRANSTON, RHODE ISLAND, ASSIGNOR TO O. C. DEVEREUX COMPANY, A CORPORATION OF RHODE ISLAND.

DESIGN FOR A CIGAR-CUTTER.

45,270.

Specification for Design.

Patented Feb. 17, 1914.

Application filed November 28, 1913. Serial No. 803,626. Term of patent 7 years.

To all whom it may concern:

Be it known that I, CARL I. OSTERBERG, a citizen of the United States, residing at Cranston, in the county of Providence and State of Rhode Island, have invented a certain new, original, and ornamental Design for a Cigar-Cutter, of which the following is a specification.

In the accompanying drawing which forms a part of this specification, the figure is a front view of a cigar cutter embodying my new design.

I claim,—

The ornamental design for a cigar cutter, as shown.

CARL I. OSTERBERG.

Witnesses:

HORATIO E. BELLOW,
FRANK STEERE.
